UNITED STATES PATENT OFFICE

MARTIN W. BRUESHABER, OF CHICAGO, ILLINOIS

MACHINE FOR CASTING STEREOTYPE PRINTING PLATES

Application filed October 30, 1926. Serial No. 145,361.

The invention relates to machines for casting stereotype printing plates and more particularly to mechanism operating automatically to strip the plate and matrix apart and to lift the plate free from the drag so that it may be readily removed therefrom for trimming or other subsequent operations.

Objects and advantages of the invention will be set forth in part hereinafter and in part will be obvious herefrom, or may be learned by practice with the invention; the same being realized and attained by means of instrumentalities and combinations pointed out in the appended claims.

15 The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

25 Fig. 1 is a side elevation showing a machine embodying the invention in the plate delivering position;

Fig. 2 is a side elevation and vertical section of the machine of Fig. 1 in plate delivering position;

30 Fig. 3 is partly a side elevation and partly a vertical longitudinal section through the machine in the plate discharging position;

Fig. 4 is a vertical transverse section on line 4—4 of Fig. 3;

Fig. 5 is a horizontal section taken on line 5—5 of Fig. 3; and

Fig. 6 is a fragmentary detail showing a manual control for the plate removing mechanism.

This application is directed to subject matter divisible from my Patent No. 1,514,757, granted November 11, 1924.

45 Figs. 3, 4, 5 and 6 herein are the same as Figs. 12, 13, 14 and 15 of the parent case. Figs. 1 and 2 of the present drawings are made from Figs. 2 and 3 of the parent case as they would appear with the mechanism of Figs. 12 to 14 thereof, that is, Figs. 3 to 5 50 of this application.

The present invention is directed to making a simple stereotype plate casting machine, very much along standard lines so far as concerns its general features, while adding thereto, or introducing thereinto, novel features and instrumentalities operating or conducting to render the machine largely automatic or approximately so; to facilitate the discharge and the handling of the hot plate preparatory to finishing; to quickly and easily strip the cast plate from the matrix and to separate or space it from the wall of the drag preparatory to its removal from the casting machine, either manually or by a machine, and to effectuate the foregoing by simple, sturdy and reliable mechanism, operating automatically in the ordinary operation, or by the usual movements, of the parts of the casting machine. Other features and objects than those enumerated will be set forth 70 in connection with the detailed description of the machine.

In the embodied form, devices are provided engaging with each end, preferably each arcuate end, of the cast plate to lift the plate clear from the matrix and the wall of the drag. Preferably in connection therewith, as embodied, a plate is cast having a tail at either end, or a tail at the bottom and a riser at the top, the plate lifting devices engaging with the two tails, and lifting the plate clear of the matrix and the drag wall, and thereby positioning the plate so that it may be removed either manually or by mechanism without danger of injury to the matrix or to 80 the plate.

As embodied further, the plate lifting members are nested in the wall of the drag during the casting operation and are projected from their nests or seats to lift the plate as described. The plate lifting members are preferably two arcuate saddles nested in recesses in the drag wall and, when projected, engaging the tails at either end of the plate to strip it from the matrix and lift it 95 free from the drag. The saddles are preferably spring pressed into their nests and are automatically moved therefrom to lift the plate from the matrix and the drag wall.

Referring to the embodiment of the inven- 100

tion illustrated by way of example in the accompanying drawings, a casting machine is shown having a vertical stationary core and a traveling drag, the plate being carried away from casting position in the drag, the drag traveling preferably to a horizontal position for the delivery or removal of the plate.

Means are provided by the invention for stripping the plate from the matrix, and for 10 removing and positioning the plate for ready removal from the drag, either manually or by the operation of the mechanism. In connection with the embodied form of such means, they operate automatically through 15 the travel of the drag, and preferably upon the plate and drag arriving at delivery position. Furthermore, the machine is preferably capacitated to cast a plate having a tail or projection at each curved end thereof, the 20 automatic plate removing means engaging these tail or projecting portions of the plate in the removing action. Other features and details of the invention will be pointed out at later points in connection with the detailed 25 description of the invention.

In said embodied form, as herein illustrated in an exemplary manner, the convex or core 1 is vertically arranged or positioned, and is preferably fixed in position upon the 30 base 2 of the machine. The core may be provided with cooling devices and the like, of any suitable or approved form, but they are not shown in the drawing as they constitute no direct part of the present invention.

35 In the embodied form, the concave or drag 3 travels to and fro between a vertical position in cooperation with the core 1 for casting the plate, and a horizontal position for the delivery of the plate, the latter position 40 being shown in Figs. 1 and 2 of the drawings. The drag may be provided with cooling devices, if desired.

Means are provided for locking the core and drag together during the casting operation, and the illustrated form thereof comprises a pair of pins or lugs 4 at one end, and upon the opposite sides, of the drag and a pair of pins 5 located at the other end of, and upon opposite sides of the drag. Cooperating 50 with the pair of lugs 4, respectively, are a pair of hooks 6, fixed on a shaft 7, which shaft is positioned transversely to the core and is mounted at the back thereof in bearings upon the machine structure. Co-operating 55 with the pair of pins 5, respectively, are a pair of hooks 8, which are fixed on a shaft 9, this shaft being likewise located transversely and at the back of the core 1 and being journaled in suitable bearings. Means 60 are provided for causing the two pairs of hooks to move concurrently or simultaneously, and as embodied, an arm 10 is fixed to shaft 7, and an arm 11 is fixed to shaft 9, these two arms being connected together by a 65 link 12. A hand lever 13 is shown for actuating

ing the mechanism just described. So far as concerns the principal features of the present invention, such fastening means may be of any suitable or approved form, and the illustrated mechanism is the same as that shown and described in the patent of Albert A. Henzi, No. 1,509,078, granted September 16, 1924.

Means are provided for traveling and guiding the drag to and fro between the plate casting and plate discharging positions, and such means may be of any suitable form so far as concerns certain features of the invention. As embodied, a pair of lugs 16 and 17 project from the back or exterior of the drag 3, and loosely carried in internal apertures in these lugs is a shaft 18, the shaft having suitable means for restraining it from longitudinal movement. Shaft 18 is likewise loosely mounted in a pair of arms 21 and 22 at one end of the arms, and at their opposite ends these arms 21 and 22 are fixed to a shaft 24, by suitable means such as pins 25 and 26. The shaft 24 is mounted to rock or partially rotate to and fro in bearings 27 and 28, formed in the machine frame 29. Suitable means are provided for so rocking or partially rotating to and fro the shaft 24, which means may be operated manually or by a machine, and as shown herein a hand lever 30 is fixed to one end of the shaft 24 for this purpose.

Also constituting a part of the means for traveling the drag to and fro, there is provided in the present embodiment, cooperating with the foregoing mechanism, a pair of pintles 35, which project from the drag 3 at the opposite sides thereof. Mounted on the respective pintles are a pair of rollers 36, these rollers running on a pair of trackways 37 formed on the opposite sides of the machine frame.

In connection with these, means are provided for locking the drag in the plate-discharging position, and as embodied, a pair of hooks 38 are pivotally mounted, respectively, on the opposite sides of the machine frame, upon corresponding pivot pins 39. The hooks 38 are provided at their forward ends with bevel faces 40, and at their opposite ends with tails 41. The operation of these locking devices will be clear from Fig. 1. The projecting ends of the pintles of rollers 35, as the drag rocks from the plate-casting position to the plate-discharging position Fig. 1, engage with the bevel faces 40 of the hooks, and the hooks thereupon swivel on their pivots to receive the pintles 35 and to thereby lock the drag in the position of Fig. 1. By rocking the hooks by means of their tails 41, they will be unlocked or disengaged from the pintles preparatory to the return travel of the drag to the plate-casting position of Fig. 1. These devices so far as concerns many features of the invention will be of any ap-

proved or suitable form, but as shown herein they are similar to those shown and described in said Patent No. 1,509,078 of Albert A. Henzi.

5 In Figs. 3 to 5 of the drawings a present preferred form of means is provided operable by the workman for actuating the saddles or plate lifting members. In this embodiment, said means is shown cooperating with 10 the recessable back in the drag behind the matrix sheet 45, and the end rings for the curved ends of the matrix are separate from the saddles or plate lifting devices. It will be understood without further amplification 15 of the drawings, that this workman-operated mechanism could be applied to the unitary form of end rings and saddles.

Referring now in detail to said embodiment shown in Figs. 3 to 5, saddles 110 of 20 arcuate form are located near each end of the drag 3, and are nested in recesses 111 in the end rings 109. The end rings 109 overhang the edges of the matrix sheet 45, as shown in Figs. 2 and 3. The saddles 110 are 25 fixed upon rods 112, respectively, which rods work in apertures transversely centrally located in the body of the drag 3. The saddles 110 are resiliently held in their seats in the respective recesses 111 by suitable means, 30 and as shown coiled springs 113 encircle the rods 112, within enlarged apertures in the drag 3, the springs being in compression between the bottoms of the apertures and collars 114, fixed on the rods 112. At their exterior ends the rods 112 are provided with 35 rollers 115.

Mounted on the machine frame, in co-operative position with respect to the two rods 112, respectively, are rods 116, mounted 40 for longitudinal reciprocation in corresponding guiding brackets or lugs 117 mounted on the machine frame.

The left hand rod 116 in Fig. 3 has its bottom end pivotally connected at 118 to an arm 45 119, which arm is fixed on a shaft 120, journaled in the machine frame. Fixed on shaft 120 is an arm 121, pivotally connected at its outer end 122 to a connecting link 123, and the other end 124 of link 123 is connected to 50 an arm 125, which is fixed to a shaft 126, journaled in the machine frame. Fixed to shaft 126 is an arm 127, which is pivotally connected at 128 to the bottom end of the other rod 116.

55 Fixed also to the shaft 126 is a pedal lever 130, and a spring 131 in tension between the machine frame and a pin 132, fixed in rod 116, tends to bring the mechanism to the position of Fig. 3. Fixed to lever 130 is a segment 133 having therein a notch 134. A 60 pedal lever 135 is pivotally supported at 136 on the machine frame, and at its opposite end 137 is pivotally connected to a rod 138 reciprocable in an apertured lug 139 on the machine frame. A coiled spring 140 is

mounted on the rod 138, in tension between lug 139 and a collar 141, fixed on the rod 138. A detent tooth 142 is formed on the upper part of the lever 135.

The manner of operation of the mechanism just described is substantially as follows:—

The rods 116 and the pedals 130 and 135 may be regarded as in the position of Fig. 2 when the drag 3 is at casting position. As the drag rocks downwardly to the position 75 of Fig. 3, the rollers 115 engage against the tops of the corresponding rods 116, and as these are locked in position by the engagement of tooth 142 with notch 134, the saddles 110 are lifted to the position of Fig. 3, lifting 80 the plate 49 clear of the matrix. The automatically operating matrix stripping devices will clear the matrix sheet 45 from the cast plate 49. These devices may be of any suitable form, such as the automatically operating clamps of the Henzi patent already referred to.

After the plate 49 is removed, the workman can step on lever 135, whereupon notch 134 will be released from tooth 142, and springs 90 113 will force the saddles 110 back into their seats 111, at the same time rocking lever 130 in clockwise direction and moving notch 134 away from tooth 142. The saddles are thus 95 out of the way in changing matrix sheets. When the drag 3 is again swung upwardly to casting position, the rollers 115 will move away from the rods 116, spring 131 will lift the rods 116, and will thereby swing lever 130 until tooth 142 again engages in notch 100 134, thereby locking the rods 116 in position to operate in the manner already described when the drag 3 again swings downwardly to plate delivering position. The foot pedal 130 may be employed to restore the mechanism to the position of Fig. 3, should this 105 be desired when the weight of the plate is on the mechanism or at any time after the release lever 135 has been operated.

Means are provided by the invention for 110 manually operating the recessable back 3' of the drag 3. This recessable back is employed partly to effect clearance and stripping of the matrix from the cast plate while the plate is still lying in position within the 115 drag, and the recessable back may have the construction and manner of operation of the similar mechanism shown and described in said Patent No. 1,509,078, of Albert A. Henzi, including the automatically operating means 120 for moving the back to and fro.

By the present invention means are provided for additionally moving the back manually, so that the back may be moved up, that is, inwardly to casting position, when the 125 matrix sheet is changed, to determine whether or not there is a true and smooth fit of the new matrix sheet as held by the side gages or stripping clamps and by the end rings when these are in casting position. 130

As herein embodied the mechanism of the recessable back may be the same as in said Patent No. 1,509,078, and the mounting of the back in the drag need not be described in detail.

5 The arm 150 is pivotally mounted at 153 in lugs 151, fixed to the recessable back 3', the arm being journaled on an eccentric 152 mounted on shaft 18. The arm 154 is fixed to eccentric 152, and its outer end is pivotally connected at 155 to a rod 156. This mechanism so far as described is substantially the same as that in the Henzi patent referred to.

10 The other end of rod 156 is not pivoted to a fixed point on the frame, but is pivoted at 158 to an arm 159, which arm is fixed on a shaft 160, journaled in the machine frame. Fixed on shaft 160 is a hand lever 161, having a spring latch mechanism 162, which has 15 a latch 163 adapted to engage with a toothed sector 164, mounted on the machine frame.

15 When hand lever 161 is left in locked position, the mechanism will operate the recessable back automatically as the drag 3 moves to and fro between plate casting and plate delivery positions, as the bearing 158 furnishes a fixed bearing whereby rod 156 may operate eccentric 152 to move the back 3 to and fro as the drag 3 travels. When drag 3 is at rest, 20 hand lever 161 can be operated by a workman and the eccentric 152 thereby rocked and the movement of the back 3 to and from casting or matrix sheet supporting position may be effected, while the drag 3 is at rest, to fit the 25 new matrix sheet in position in the drag, or to preliminarily inspect its condition prior to casting, or for other purposes as may be convenient or desirable.

30 The invention in its broader aspects is not limited to the specific mechanisms shown and described but departures may be made therefrom within the scope of the accompanying claims without departing from the principles of the invention and without sacrificing its 35 chief advantages.

40 45 What I claim is:—

1. A machine for casting stereotype plates including in combination cooperating casting members including a drag having a recessable back behind the matrix and means for moving the recessable back to and from casting position.

50 55 2. A machine for casting stereotype plates including in combination cooperating casting members including a drag having a recessable back behind the matrix and means for moving the recessable back away from the matrix.

60 65 3. A machine for casting stereotype plates including in combination cooperating casting members including a drag having a recessable back behind the matrix and means operable by an attendant for moving the recessable back to supporting position behind the matrix.

4. In a stereotype plate casting machine an end ring overhanging the matrix edge and a plate lifter moving independently from the end ring for lifting the cast plate from the matrix.

70 5. In a stereotype plate casting machine an end ring overhanging the matrix edge and a plate lifter moving independently from the end ring for separating the cast plate from the matrix.

75 6. In a stereotype plate casting machine a stationary end ring overhanging the end of the matrix sheet and a movable plate lifter for separating the cast plate from the matrix.

80 7. In a stereotype plate casting machine an end ring overhanging the matrix edge and a plate lifting device exterior to the end ring for lifting the plate from the matrix.

85 8. In a stereotype plate casting machine a curved end ring overhanging the matrix sheet on its convex side and a plate lifting device engaging the convex side of the plate.

90 9. In a stereotype plate casting machine a curved end ring overhanging the matrix sheet on its convex side and a plate lifting device engaging the convex side of the plate exteriorly to said end ring.

95 10. A stereotype plate casting machine including in combination casting mechanism including a drag, a pair of end rings overhanging the edges of the matrix and means movable relatively to the end rings for lifting the cast plate from the matrix.

100 11. A stereotype plate casting machine including in combination casting mechanism including a drag, a pair of end rings overhanging the edges of the matrix and means located exteriorly to and movable relatively to the end rings for lifting the cast plate from the matrix.

105 12. A machine for casting stereotype plates including in combination cooperating casting members including a drag having a recessable back behind the matrix and means for moving the recessable back to and from casting position and means for lifting the plate from the drag.

110 13. A machine for casting stereotype plates, comprising a drag having a recessable back behind the matrix, means for moving said recessable back, and automatically operated means for lifting the cast plate from the drag.

115 14. A machine for casting stereotype plates, comprising a drag having a recessable back behind the matrix, means operated automatically by the movement of the drag to and from casting position for moving the recessable back to and from casting position, and means operating automatically for lifting the cast plate from the drag.

120 15. A machine for casting stereotype plates, comprising an end ring, a plate lifting device movable with respect to said ring and nested

therein, and means for moving said plate lifting device with respect to the end ring.

16. A machine for casting stereotype plates, comprising an end ring overhanging the edge of the matrix sheet, a plate lifting device movable with respect to the end ring and nested in a recess therein, and means for moving said plate lifting device with respect to the end ring.

10 17. A machine for casting stereotype plates, comprising a drag having a recessable back behind the matrix, an end ring overhanging the edge of the matrix, and means for lifting the cast plate from the matrix.

15 18. A machine for casting stereotype plates, comprising a drag having a recessable back behind the matrix, end rings the inner edges of which overhang the edges of the matrix, and means movable independently of the end

20 rings, for lifting the cast plate away from the matrix.

19. A machine for casting stereotype plates, comprising a drag, end rings associated with the drag for engaging the matrix, and lifting means for lifting the cast plate from the matrix, the matrix being held in position by the end rings ready for the next casting operation.

25 20. A machine for casting stereotype plates, comprising a drag, end rings associated with the drag for engaging the matrix, and lifting means nested in the end rings for lifting the cast plate from the matrix, the matrix being held in position by the end rings ready for the next casting operation.

21. A machine for casting stereotype plates, comprising a drag, having a recessable back, end rings associated with the drag for engaging the matrix, and lifting means for lifting the cast plate from the matrix, the matrix being held in position by the end rings ready for the next casting operation.

30 22. A machine for casting stereotype plates, comprising a drag, end rings associated with the drag for engaging the matrix, and lifting means passing through the drag for lifting the cast plate from the matrix, the matrix being held in position by the end rings ready for the next casting operation.

35 23. A machine for casting stereotype plates, comprising a drag, end rings overhanging the edges of the matrix sheet associated with the drag, lifting saddles for lifting the cast plate from the matrix, the matrix being held in position ready for the next casting operation by the overhanging parts of the end rings.

40 24. A machine for casting stereotype plates, comprising a drag, end rings overhanging the edges of the matrix sheet associated with the drag, lifting saddles nested in the end rings for lifting the cast plate from the matrix, the matrix being held in position ready for the next cooling operation by the overhanging parts of the end rings.

45 25. A machine for casting stereotype plates including in combination cooperating casting members including a drag having a recessable back for supporting the back of the matrix, means manually operable by an attendant and automatically operable when the drag reaches a predetermined position for moving the recessable back to and from casting position.

50 26. A machine for casting stereotype plates including in combination cooperating casting members including a drag having a recessable back behind the matrix, means operatively connected with the recessable back for moving it to and from casting position, and means actuated either by an attendant, or actuated when the drag reaches a definite predetermined position, for moving the first mentioned means.

55 In testimony whereof, I have signed my name to this specification.

MARTIN W. BRUESHABER.
